(57) **CLAIM**

The ornamental design for a reconfigurable ring set, substantially as shown and described.

DESCRIPTION

FIG. 1 is a perspective view depicting a reconfigurable ring set;

FIG. 2 is a perspective view depicting a reconfigurable ring set;

FIG. 3 is a top plan view of the reconfigurable ring set shown in FIG. 1, a bottom plan view is identical;

FIG. 4 is a left side elevational view of the reconfigurable ring set shown in FIG. 1, a right side elevational view is identical;

FIG. 5 is a cross-sectional view taken on line 5—5 view of the reconfigurable ring set shown in FIG. 1; and,

FIG. 6 is a perspective exploded view of the reconfigurable ring set shown in FIG. 1.

The broken lines in FIGS. 1 and 2 are for environmental purposes only and form no part of the claimed design.
